UNITED STATES PATENT OFFICE.

LIPA POLINKOWSKY, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,406,221.

Specification of Letters Patent. Patented Feb. 14, 1922.

Application filed June 5, 1919. Serial No. 301,932.

To all whom it may concern:

Be it known that I, LIPA POLINKOWSKY, a citizen of Russia, residing at New York, in the county of New York, State of New York, have invented certain new and useful Improvements in Telephone-Exchange Systems, of which the following is a full, clear, concise, and exact description.

This invention relates to telephone systems in which machine switching apparatus is employed for establishing connections between subscribers' lines.

More particularly, this invention is applicable to a telephone system of this character in which message registration is accomplished by providing the several subscribers' lines with message registering devices, such that at the completion of a successful call the register associated with the calling line 20 will be operated to charge the message.

The object of the present invention is the provision of a testing mechanism which is operative in response to certain conditions brought about as a result of a telephone connection having been established to make a test of the subscribers' lines in order to determine the condition thereof.

A feature of the invention consists in the provision of a testing mechanism at the exchange arranged in common to a plurality of lines, and which becomes operative in response to the release of an established connection between any one of such lines and any other subscriber's line to perform a test of all lines with which it is associated to ascertain whether such lines are in a standard or an unstandard condition.

A further feature resides in the provision, in a telephone system of the above described character where message registers are associated with the subscribers' lines, of a testing apparatus responsive to the release of an established connection to perform a test of all lines to which it has access to determine the condition of such lines, and further to determine if the message register on the line which initiated the connection was successfully operated, either to charge the call, if successful, or to restore the meter to normal 50 in case the call did not succeed.

A further feature consists of a common testing switch associated with a plurality of subscribers' lines operated automatically through a complete cycle in response to the 55 disestablishment of a connection to test the

condition of said lines, and which is arranged to stop, when a line is located having an unstandard condition thereon, in a position in its cycle corresponding to such line, and to thereupon effect the operation of a 60 trouble signal.

Other and further features of the invention will become apparent from the following description and appended claims.

In the drawings, Figs. 1 and 2 taken together illustrate a subscriber's line appearing in the exchange in a first line finder, which, with a second finder switch and succeeding selector switches, is arranged to extend said line into connection with other 70 lines. There is also shown a message register associated with the subscriber's line at the substation, and at the exchange a testing mechanism common to a plurality of subscribers' lines.

Fig. 3 shows a party line having two substations, each provided with message registers.

Fig. 4 illustrates a party line having four substations thereon, each of which is 80 equipped with a message register.

Fig. 5 shows a modification of the invention in which the common testing mechanism is associated with a plurality of cord circuits at the first line finders.

Referring particularly to Figs. 1 and 2, the subscriber's line is provided at the substation with a message register consisting of a polarized magnet 180 connected from one side of the line to ground through a pair of springs 182 and 183. An operating plunger 181 is arranged to be set by the subscriber to complete the circuit of the magnet 180 through the springs 182 and 183, such that when metering current of a given polarity 90 is impressed upon the line, the magnet 180 will operate its armature in one direction to release the set plunger 181 and charge the call. When current of the opposite polarity is placed on the line, the magnet 180 is designed to operate its armature in the opposite direction to release the plunger 181 without registering the call.

Considering the message register shown in Fig. 1, a description will be given of the 105 structural arrangement and the manner in which the same is designed to operate. When all parts of the register are in their normal positions, the plunger 181 is disposed, as shown in the drawing. To initiate 110

a call the subscriber depresses the plunger 181, moving the same longitudinally against the pressure of spring 159. As the plunger advances, the pin 135 thereon engages the finger 146 of the dog 136, rotating the latter in a clockwise direction against the tension of spring 137. The rotation of dog 136 permits its member 145 to disengage the inner surface of arm 147 of the bell crank lever 148. Lever 148 being thus released is rotated in a clockwise direction about its axis by means of the spring 149. Arm 154 of the lever 148, bearing on the projection 155 of member 156, causes said member, which is pivoted on the same axis with lever 148, to rotate in a clockwise direction against the tension of spring 157. Furthermore, the arm 154 depresses the spring 182 into contact engagement with spring 183, whereby the conductor 113 is connected through the windings of magnet 180 to ground. After the plunger 181 has been moved to the full extent of its stroke, during which time pin 135 passes by the finger 146, it is released and permitted to return by the pressure of spring 159. On the return movement of plunger 181, pin 135 engages the tip end of finger 146 and since the projection 139 of dog 136 engages the stop pin 138, said plunger is prevented from restoring to its normal position.

When the connection is disestablished in a manner to be explained in detail herein-after, current of either positive or negative polarity is applied to conductor 113 to operate the armature 144 in one direction or the other. Assume first that the applied current is of the proper polarity to rotate the armature 144 in a counter-clockwise direction. This rotation of the armature 144 causes the member 161, attached to said armature, to swing toward the right. The insulated roller 158, carried on member 161, which normally engages a notch in spring 183 is caused to disengage such notch and to move onto the plane portion of the spring 183. The effect of this movement is to flex the springs 182 and 183 upwardly and to rotate the bell crank lever 148 in a counter-clockwise direction against the tension of spring 149. The engagement of arm 147 with projection 145 of the dog 136 again rotates said dog against the tension of spring 137 to a point where finger 146 moves out of holding relation with the pin 135. The rotation of lever 148 also permits the member 156 to restore to its normal position. The disengagement of pin 135 from finger 146 permits spring 159 to restore the plunger 181 to normal. Shortly after plunger 181 is released, the lever 148 continuing to rotate under the action of springs 182 and 183, arm 147 disengages the inner surface of projection 145, whereby the dog 136 quickly rotates against the stop pin 138 and pro-

jection 145 assumes the position shown in the drawing, locking the lever 148 in place.

At the same time the armature 144 rotates to restore the plunger 181, as described, it also actuates the pawl 132 to engage the next notch in the register counting wheel 131. As soon as current ceases to flow in conductor 113, the armature 144 assumes its normal position and insulated roller 158 again engages the notch in spring 183 whereby this spring becomes disconnected from the spring 182. The restoration of armature 144 also removes pressure from the pawl 132, which operates in the well-known manner to advance the counting wheel 131 one position.

In case current of the opposite polarity is applied to conductor 113, the armature 144 is rotated in a clockwise direction. This time the roller 158 moves onto the plane portion of spring 183 to the left of the indentation and the plunger 181 is restored to its normal position in exactly the same manner as above described. Due to the opposite rotation of armature 144, however, the pawl 132 is not operated as before and consequently the register counting wheel 131 is not advanced.

At the exchange the subscriber's line terminates in the terminals 110, 118, 119 and 121 of a first line finder. A marginal relay 108, as will be hereinafter explained, is arranged to operate in response to an increased potential which is placed upon the terminal 118 during the release of the connecting apparatus in the exchange, if the call has been successful, to connect the high potential metering battery 111 to the subscriber's line. On the other hand, in case the call is not successful, the release of the connecting apparatus does not impress a high potential upon the terminal 118 and hence relay 108 remains deenergized to connect metering battery 114 of opposite polarity to the subscriber's line. When the subscriber initiates a call, his line is extended in the well-known manner by a first and second line finder, diagrammatically shown at 185 and 186, to a group selector. By manipulating his calling dial the group selector 187 and succeeding selector switches, such as selector 188, may be operated to complete the extension of a connection to the desired line. Since the present invention has to do with a testing arrangement for testing subscribers' lines and is not concerned with the connecting apparatus for establishing the telephone connection nor with the particular method of impressing a high potential current upon the third or test conductor during the release period of the connection for the purpose of effecting message registration on the calling line, it is believed to be necessary to show only so much of a telephone system of this character as will

clearly illustrate the method of operation of such testing mechanism. For a complete understanding of the operation of a system to which this invention is applicable where 5 first and second line finders, group and final selectors are employed, and in which the release of an established connection serves to place a high potential current upon the test conductor of the calling line to operate a 10 marginal relay if the call was successful, or to withhold the application of such high potential, if the call was unsuccessful, for metering purposes during the time that the connection is being disestablished, reference 15 is made to the patent to Polinkowsky No. 1,193,053, issued August 1, 1916.

Assume that the subscriber at the substation shown in Fig. 1 desires to extend a connection to another subscriber's line, such as 20 the line shown in Fig. 2. He first depresses the plunger 181 to connect ground through the magnet 180 to the conductor 113. Upon removing the receiver, a circuit is then established from battery through the winding 25 of the line relay 101, right-hand armature and contact of relay 105, conductor 112 through substation apparatus, magnet 180 to ground. Current in this circuit is insufficient to operate magnet 180 but does cause 30 the relay 101 to attract its armature. Relay 101, by operating, closes the circuit over the left-hand winding of the common starting relay 104 through the resistance 102, to the terminal 110, whereby a selectable potential 35 is placed upon such terminal at the first line finders. Relay 104 by attracting its armature places a ground upon the starting conductor 184 which serves in the well-known manner to start in operation all idle line 40 finders which have access to the calling line. The connection of a first line finder, a second line finder, and the subsequent extension of the call over selector switches to the called line, is well understood and need not 45 be described herein. As soon as a first line finder has stopped with its brushes upon terminals 110, 118, 119, 121, a circuit is completed from battery through the winding of relay 107, and in parallel therewith 50 through the right-hand winding of relay 108, left-hand winding of relay 109, terminal 118 and thence to ground at the first line finder. Relays 107 and 109 attract their armatures, but relay 108 being marginal 55 remains inactive. A circuit is now closed from battery through the winding of the cut-off relay 105, armature and contact of relay 109 through the right-hand winding thereof to ground. Relay 105 opens the circuit of the line relay 101 which permits the 60 starting relay 104 to deenergize, provided another subscriber of the same group is not calling, and removes the calling condition from terminal 110.

65 If the call were unsuccessful when the

calling subscriber replaces his receiver to the switchhook, and the switches in the exchange restore to normal condition, no high potential current is impressed upon terminal 118. As soon as the holding circuit for relay 107 and the energizing circuit of relay 109 is opened by the release of the connection, relay 107 deenergizes. A circuit is thereupon established from battery through the winding of relay 105, armature and contact of relay 109 to ground at the left-hand armature and contact of relay 107 in shunt of the holding circuit through the right-hand winding of relay 109. This causes the release of relay 109, which in turn opens the 70 circuit for relay 105, but relay 105 being slow to release, retains its armatures for an interval. During this period, high potential current of negative polarity from the battery 114 is applied to the conductor 113 75 to operate the polarized magnet 180 to restore the plunger 181 without registering the call. Circuit for this battery may be traced through the pilot lamp 115, relay 116, right-hand armature and contact of relay 107, ar- 80 mature and back contact of relay 108, front contact and left-hand armature of relay 105 to the conductor 113. As soon as relay 105 deenergizes, line relay 101 is again con- 85 nected to the line. 90

Assume now that the calling subscriber succeeds in extending a connection to the called line and that the called subscriber responded. When at the end of the conversation the receivers are replaced on the switchhooks and the connection is disestablished, a high potential is impressed upon the terminal 118 of the first line finder. This additional flow of current through the right-hand winding of marginal relay 108 is sufficient to cause such relay to attract its armature. A circuit is established from the high potential battery 111 of positive polarity through the relay 117, left-hand winding, front contact and armature of relay 108, 100 front contact and left-hand armature of relay 105, conductor 113 through the polarized magnet 180 to ground. This current serves to release the plunger 181 and also to advance the register 181 to charge the call. 105 As soon as the marginal current which is only temporarily applied to the terminal 118 is removed, relay 107, the right-hand winding of relay 108 and the left-hand winding of relay 109 are deenergized. The right- 110 hand winding of relay 109 is again short-circuited and such relay thereupon releases its armature, causing in turn the release of relay 105. When the relay 105 releases, the circuit from battery 111 is opened, register 115 magnet 180 deenergizes and also the left-hand winding of relay 108 becomes deenergized and such relay releases its armature. 120

Should the magnet 180 fail to operate 125 properly at the completion of a call to re- 130

move ground from the conductor 113; should the subscriber operate the plunger 181 to connect ground to the conductor 113, and then abandon the call, or should, for any other reason, a ground potential occur upon the subscriber's line, means embodying the subject matter of the present invention is provided at the exchange for detecting the presence of such an unstandard condition. This means consists of a testing switch 120 which is common to a plurality of lines, and which is started in operation at the termination of a call on any one of the lines to which it is common to make a test thereof for the purpose of determining whether or not any of such lines is connected to ground. The switch 120 has a plurality of contacts such as 123, which are closed in successive positions to the successive conductors 113 of the lines with which this switch is associated. As shown, the line conductor 113 is connected to the sequence switch contact 123 closed in the seventh position thereof. As has been seen, whenever a connection is established from one subscriber's line to another, the disestablishment of such connection serves to connect either the metering battery 111 to the calling line or the battery 114, dependent upon whether the call was successful or not. In either event, when the connection is released, one or the other of the pilot relays 117 and 116 will be energized. These relays upon energizing close a circuit from ground over their armatures and contacts through sequence switch contact 122 in position 1, winding of the sequence switch magnet 120 to battery and ground. The sequence switch 120 thereupon starts in operation and continues to move by means of an energizing circuit including contact 122 bottom, closed in positions 2 to 18 inclusive, back contact and armature of relay 124 to ground. As sequence switch 120 passes through its successive positions, a circuit is closed from battery through the winding of the sensitive test relay 124, through contacts, such as 123, to the conductor 113 of lines corresponding to such successive positions. Should a ground be present on the conductor 113 of the subscriber's line shown, a circuit is established from battery through the relay 124, sequence switch contact 123, position 7, back contact and left-hand armature of relay 105 to the conductor 113. Relay 124 thereupon energizes and opens the circuit of sequence switch 120, arresting the movement thereof. At its front contact, the test relay 124 closes a circuit for a trouble signal, such as lamp 125. This trouble circuit may be of any desired character. Should some other subscriber's line be busy during the time that the testing switch 120 is passing through its cycle, no circuit would be complete to disturb such line, as the switch 120 passes through its position

corresponding thereto. This is true since the test circuit leads through the back contact and armature of relay 105 which, in case of a busy line, will be energized.

If desired, a test may be made of the lines to which the switch 120 has access by the depression, at any time, of the manual key 127.

In Fig. 3, the substations of the party line are of the well-known type where the ringer 133 of one substation is connected to ground from one side of the line, whereas the ringer 193 at the other substation is connected from ground to the other side of the line. Both the polarized message register magnets 130 and 190 are connected to the same side of the line. A subscriber desiring to initiate a call may first remove his receiver and listen to determine whether the party line is free, before depressing the metering button.

In Fig. 4, where four substations are arranged on the party line, each is provided with a relay 142, 152, 162 and 172 connected in bridge to the line, which respond to a ringing current sent from the exchange, and when energized connect the polarized ringers 143, 153, 163 and 173 respectively to the wires of the party line. Two of these polarized ringers are shown connected to one side of the line, whereas the other two are connected to the other side of the line. Each substation is equipped with a polarized message register magnet such as 140, 150, 160 and 170, all of which are connected to the same side of the line.

When the number of lines provided with message registers is comparatively large, an arrangement is used, as shown in Fig. 5, whereby the lines are connected in the exchange to a separate group of first line finders so that each line needs to be provided only with a cut-off relay 307 and a line relay 301. This is accomplished by associating the relays, which perform the message registration together with the common testing switch, with the first line finder instead of the incoming line.

When a call is initiated, a circuit is established for the line relay 301 which energizes and places a selectable potential from battery through the left-hand winding of starting relay 304 on the terminal 310. Relay 304 by energizing, closes a circuit from ground over its armature and contact through the winding of the power magnet 311, back contact and armature of relay 312, back contact and left-hand armature of relay 313 to battery and ground. This circuit is also extended in multiple to the power magnets of all other idle first line finders serving the calling line. Power magnet 311 operates in the well-known manner to bring the brushes of the line finder in contact with the terminals of the subscriber's line. When the terminal 310 of the calling line is reached, a circuit is closed from such terminal 310 to the left-hand contact of relay 304, and the line relay 301 is energized. The line relay 301 places a selectable potential from battery through the left-hand winding of starting relay 304 on the terminal 310. Relay 304 by energizing, closes a circuit from ground over its armature and contact through the winding of the power magnet 311, back contact and armature of relay 312, back contact and left-hand armature of relay 313 to battery and ground. This circuit is also extended in multiple to the power magnets of all other idle first line finders serving the calling line. Power magnet 311 operates in the well-known manner to bring the brushes of the line finder in contact with the terminals of the subscriber's line. When the terminal 310 of the calling line is reached, a circuit is closed from such terminal 310 to the left-hand contact of relay 304, and the line relay 301 is energized.

5 minal through the right-hand high resistance winding of test relay 314. Relay 314 energizes and closes a circuit through its left-hand low resistance winding, winding of test relay 312 to ground, which being of low resistance reduces the potential on terminal 310 to render the calling line busy. Relay 312, by operating, opens the power circuit, 10 brings the finder to rest, and also closes a circuit from battery through the left-hand armature and contact of relay 313, armature and front contact of relay 312 to the terminal 330 of a second line finder, thereby placing a selectable condition thereon. In 15 parallel therewith, a circuit is also closed for the common starting relay 316 which operates in the well-known manner to start the idle second line finders in operation. During the extension of the connection, a 20 circuit is completed over the contact 338 for relay 337 and the right-hand winding of relay 348. Relay 337 operates and closes a circuit over its left-hand armature for relay 335, which in turn completes a circuit for relay 313. Relay 313 opens the circuit for starting relay 316 to bring the second line finders to rest. Relay 348, being marginal, however, does not receive sufficient current to operate at this time. The 25 circuit of relay 313 includes the cut-off relay 307 which in operating opens the circuit of line relay 301.

After the extension of an unsuccessful call when the switches in the exchange are 30 released, no metering battery is placed upon the terminal 338 and therefore relay 348 does not energize. As soon as the circuit of relay 337 is opened, it releases its armatures. At the left-hand armature of relay 337 a 35 circuit is closed in shunt of the winding of relay 335. This causes the relay 335 to de-energize slowly. At the right-hand contact of relay 337, a circuit is now completed from the metering battery 344 through relay 346, 40 right-hand contact of relay 337, back contact and armature of relay 348, right-hand armature and contact of relay 313, which remains energized until relay 335 releases, to the subscriber's line over conductor 343. 45 This serves, as has already been explained, to release the meter at the calling substation without charging the call.

After a successful call has been extended, and the switches released at the termination 50 of the conversation, a metering battery is placed upon the terminal 338. The added flow of current is sufficient now to operate the right-hand winding of relay 348. A circuit is thereupon completed from the battery 55 341 of opposite polarity through winding of relay 347, left-hand winding, front contact and armature of relay 348, right-hand armature and contact of relay 313 to the subscriber's line. The register is operated

at this time to be restored and also to charge the call.

The common testing sequence switch 320 operates in the same manner as has been already described in connection with testing switch 120 to perform a testing operation of all lines to which it has access, as soon as a call involving any one of such lines as a calling line, has been completed.

What is claimed is:

1. In a telephone system, subscribers' lines, 75 means for establishing a connection between two of said lines, a multi-position testing switch for testing said lines, and means responsive to the disestablishment of said connection for operating said testing switch. 80

2. In a telephone system, subscribers' lines, 85 automatic switches for establishing a connection between two of said lines, a multi-position testing switch for testing said lines, and means responsive to the disestablishment of said connection for operating said testing switch.

3. In a telephone system, subscribers' lines, 90 automatic switches for establishing a connection between said lines, a testing device for testing said lines, means operated each time said switches are taken for use for initiating the operation of said testing device, and manually operable means for initiating the operation of said device. 95

4. In a telephone system, subscribers' lines, 100 automatic switches for establishing a connection between said lines, a testing device for testing said lines, and means operated each time said switches are taken for use for operating said testing device.

5. In a telephone system, a plurality of subscribers' lines, automatic switches for establishing a connection between said lines, a testing device common to said lines for 105 testing the condition thereof, and means operative in response to the disestablishment of said connection for initiating the operation of said device.

6. In a telephone system, subscribers' lines, 110 means for establishing a connection between said lines, a testing device common to a plurality of said lines, and means operative in response to the disestablishment of a connection between one of said plurality of lines 115 and any other of said subscribers' lines for operating the testing device.

7. In a telephone system, subscribers' lines, 120 means for establishing a connection between said lines, a testing device common to a plurality of said lines, means operative in response to the disestablishment of a connection between two of said lines for initiating the operation of said device, and means for stopping said device whenever a line is found 125 having an unstandard condition thereon.

8. In a telephone system, subscribers' lines, 130 automatic switches for establishing a con-

- nection between said lines, a common testing device for testing the condition of said lines, means operative in response to the disestablishment of a connection between said lines
- 5 for initiating the operation of said device, means for stopping said device whenever a line is found having an unstandard condition thereon, and a signal operated by said testing device.
- 10 9. In a telephone system, subscribers' lines, automatic switches for interconnecting said lines, a common testing switch for testing the condition of said lines, said switch having a position for each of the lines with
- 15 which it is associated, means responsive to the disestablishment of a connection between said lines for initiating the movement of the testing switch, means for automatically continuing the movement of said testing switch
- 20 through its successive positions, and means for arresting the movement of said testing switch in position corresponding to any line upon which an unstandard condition exists.
10. In a telephone system, subscribers' lines, message registers for said lines, means
- 25 for interconnecting two subscribers' lines, a testing device common to said lines, means responsive to the disestablishment of a connection for operating a message register, and means also responsive to the disestablishment of said connection for operating the testing device to determine if said register has operated correctly.
11. In a telephone system, subscribers' lines, message registers on said lines, switches for interconnecting said lines, means effective as a result of the establishment of a connection between two subscribers' lines to operate the register on the calling line, a testing switch for testing the condition of a plurality of said lines, means operative upon the disestablishment of said connection for initiating the movement of said testing switch, and means for stopping such switch when a line is found upon which the message register has not been properly operated.
